UNITED STATES PATENT OFFICE.

JAMES F. McELROY, OF ALBANY, NEW YORK, ASSIGNOR TO CONSOLIDATED CAR HEATING COMPANY, A CORPORATION OF WEST VIRGINIA.

DYNAMO FOR TRAIN-LIGHTING.

SPECIFICATION forming part of Letters Patent No. 777,857, dated December 20, 1904.

Original application filed June 6, 1902, Serial No. 110,413. Divided and this application filed September 2, 1904. Serial No. 223,072.

To all whom it may concern:

Be it known that I, JAMES F. McELROY, a citizen of the United States, residing at Albany, county of Albany, and State of New York, have invented certain new and useful Improvements in Dynamos for Train-Lighting, of which the following is a specification describing that form of my invention which I now regard as the best form out of the various forms in which it may be embodied.

Reference is made to the accompanying drawings, wherein—

Figure 1 is a plan of the machine. Figs. 2 and 3 show details of the reversing apparatus.

My invention involves certain improvements in the construction and arrangement of dynamo-electric machines, with particular reference to the mounting of the same upon the truck of a railway-vehicle, so as to be driven by one of the axles to supply electricity for lighting and other purposes upon the car or upon the train of which the car forms a part.

I have devised a certain novel way of mounting the automatic switch devices in connection with the rest of the dynamo-machine in order that the whole may form a unitary structure.

Referring to the accompanying drawings, A represents a dynamo-electric machine inclosed, as usual, by an iron casing formed by an extension of the neutral portion of the field-magnet structure into a box form, within which is mounted the armature of the machine and outside of the armature the field-magnet coils and pole-pieces. No novelty is claimed for this general construction, so it need not be described in detail. I have, however, added at the rear end of the machine, opposite to the commutator end, an extension B, which is made hollow, so as to contain the journal-bearings, and also, in a separate compartment, the reversing-switch that controls the direction of current-flow. Fig. 3 shows the lower half of the extension B, the upper half thereof being formed integral with the upper half of the main casing of the machine, so as to be movable therewith in a manner to be hereinafter described. The lower half is in like manner connected to the lower half of the main casing. This division of the exten-

sion B is shown in Fig. 2, wherein B' is the upper part, and B² the lower part, of the extension. A cover B³ is also provided, which has suitable hinges and a latch B⁴.

Referring to Fig. 3, C is the armature-shaft, extending through journal-box D, which rests in the partition-wall E of the extension B. On the extremity of the shaft C is a disk F, provided with a flange F', projecting from the periphery of the disk on the side away from the machine itself. Opposite the disk F are placed two disks F² and F³, the former being attached to the outer end of a pivoting-stud F⁴, set in a socket projecting from the center of a circular plate G, which sets into and covers over an opening in the wall of the casing and is held therein by a latch G'. The disk F³ is stationary, being carried by the projecting socket aforesaid, while the disk F² is free to turn to a limited extent by the rotation of the stud F⁴ in its socket.

As appears in Fig. 2, the stationary disk F³ is provided with a curved slot f, through which projects a pin H, secured at its base to the disk F² and serving to limit by its engagement with the ends of the slot the rotation of said disk F². The pin H also passes through an eye on one end of the spring-lever J.

On the inside of the flange F' of the disk F is pivoted a pawl K, the tip of which bears upon the periphery of both disks F² and F³. The pawl is pivoted at the point k and is normally pressed downward against the disks by the spring k'. On the periphery of the disk F² is a notch L, while the upper half of the disk F³ is shaped on a curve having a somewhat shorter radius than the rest of the disk, the reduction from the larger and normal radius of the lower part to the smaller radius of the upper part being made gradually, so that the disk has the effect of a cam to lift the tip of pawl K out of the notch L when the notch comes opposite either extremity of the reduced portion aforesaid of the disk F³.

M is a reversing-switch comprising four stationary terminals 1, 2, 3, and 4, each being split to receive one of the knife-blade-switch levers O and O'. The contact-terminals 1 and

2 are mounted on the upper side of an insulating-block P, secured to the walls of the casing, and between them is pivoted the switch-plate O. In like manner the terminals 3 and 4 and the switch-blade O' are attached to the under side of the insulating-block P. The two switch-plates are operated simultaneously by the spring-arm J through the intervention of an insulating-block R, which is pivotally connected, as shown in Fig. 4, to both of the switch-plates O and O'.

The operation of the devices described is as follows: Assuming that the armature-shaft starts to rotate, for instance, in a clockwise direction, when the parts are in the position shown in Fig. 2 it will carry with it the disk F and the pawl K, pivoted thereto, within the flange F'. The tip or hook of the pawl will slide around the periphery of the disks F² and F³ until it is permitted by the reduced portion of disk F³ to drop into the notch L, whereupon it catches the disk F² and turns it until the notch L comes opposite the succeeding cam-surface of the disk F³, which will lift the pawl K out of the notch L and will thereafter ride freely on the peripheries of both disks. The movement of the disk F² has carried with it the pin H and the lever J, which in turn draws on the switch-plates O and O', and thereby throws the switch to the proper position corresponding to the clockwise direction of rotation of the shaft C. If the dynamo starts up again in the opposite direction, the pawl K will in like manner take into the notch L and throw back the disk F² into the position shown in Fig. 2. It will be observed that the switch M, which is thus operated by the movement of the dynamo in one direction or the other, is contained within a separate inclosure within the projection B, extending out from the main casing of the machine.

This application is a division of my application, Serial No. 110,413, filed June 6, 1902.

45 The particular construction of the switch-operating mechanism is not herein claimed, as it is made the subject of my Patent No.

739,205, dated September 15, 1903. My purpose in the present application is to claim the construction and mounting of the switch and 50 switch-operating mechanism with relation to the rest of the dynamo, whereby these devices are separated from the armature and other parts and yet the whole forms a unitary structure.

55 What I claim as new, and desire to secure by Letters Patent, is—

1. In a dynamo-electric machine, the combination with a field-magnet, of a casing forming the yoke of said magnet and inclosing the machine, a partition in said casing surrounding the dynamo-shaft, an armature on said shaft on one side of the partition, an automatic switch on the opposite side of said partition, and operating devices controlled by the 60 shaft and controlling said switch.

2. In a dynamo-electric machine, the combination with a field-magnet, of a casing forming the yoke of said magnet and inclosing the machine, a partition in said casing surrounding the dynamo-shaft, a bearing for the shaft in said partition, an armature on said shaft on one side of the partition, an automatic switch on the opposite side of said partition, and operating devices controlled by the 70 shaft 75 and controlling said switch.

3. In a dynamo-electric machine, the combination with a field-magnet, of a casing forming the yoke of said magnet and inclosing the machine, a partition in said casing pierced by 80 the dynamo-shaft, an armature on said shaft on one side of the partition, an automatic switch on the opposite side of said partition, and operating devices mounted on the shaft 85 on the same side of the partition as the switch and controlled by the shaft but controlling the said switch.

In witness whereof I have hereunto set my hand, before two subscribing witnesses, this 12th day of August, 1904.

JAMES F. McELROY.
